UNITED STATES PATENT OFFICE.

THOMAS M. CHAPMAN, OF WORTHAM, TEXAS.

COOLER.

1,290,085.

Specification of Letters Patent.

Patented Jan. 7, 1919.

Application filed January 26, 1918. Serial No. 214,002.

To all whom it may concern:

Be it known that I, THOMAS M. CHAPMAN, a citizen of the United States, residing at Wortham, in the county of Free-
5 stone and State of Texas, have invented new and useful Improvements in Coolers, of which the following is a specification.

This invention relates to refrigerating apparatus, wherein one or a plurality of chambers will be retained in a cooled condition without the employment of ice.

In carrying out the invention, I propose to produce an iceless refrigerator, constructed of any number of chambers, each comprising a shelf with pans arranged above and below the shelf, the chambers being surrounded by a fabric sheet which has both of its ends arranged in the pans and which, by capillary attraction, becomes saturated 20 by water in the upper pans, presenting an evaporating as well as a cooling, dust and insect obstructing outer surface for the chambers.

It is a further object of the invention to 25 produce an iceless refrigerator constructed to provide any desired number of chambers, each of said chambers comprising a shelf with pans arranged above and below the shelf, each of said chambers being fur-
30 ther provided, at the top thereof, with suitable ventilating means, the uppermost pan having arranged thereover a water tank having means for regulating the outlet there-
from into the said upper pan, each of the 35 chambers being surrounded by a fabric sheet which has both of its ends arranged in the pans so as to become saturated with the water both by capillary attraction and by the outflow of water from the water tank
40 causing the said water to slowly drip over the entire surface of the fabric sheets to retain the chambers in a cooled condition, and also to permit of a certain quantity of water being received on the lower pan, and
45 whereby each of the chambers provides a dry shelf and a wet shelf, the lower water pans constituting the latter so that the device will accommodate various classes of articles or food to retain the same in the
50 desired cool condition.

It is a still further object of the invention to produce a device of this character which may be readily knocked down or folded, when not desired for use, to present
55 a small package for storage or shipment.

It is a still further object of the inven-

tion to produce an iceless refrigerator that shall be of an extremely simple construction, comparatively cheap to manufacture, automatic in its action and thoroughly efficient for the purpose intended.

Other objects and advantages will appear as the nature of the invention is better understood, reference being had to the accompanying drawings, in which,

Figure 1 is a perspective view of an iceless refrigerator constructed in accordance with this invention.

Fig. 2 is an approximately central vertical longitudinal sectional view through the same.

Fig. 3 is a sectional view taken approximately at a right angle to Fig. 2.

Fig. 4 is a fragmentary perspective view illustrating the manner in which the supports for the chambers may be disconnected to permit of the collapsing of the device.

Fig. 5 is a detailed sectional view showing the manner in which the water may be automatically fed to the fabric sheets.

Fig. 6 is a fragmentary perspective view of one of the shelves.

In the construction of my improved refrigerating device, disclosed by the drawings, I have illustrated an upper chamber A 85 and a lower chamber B, and in this connection, it is to be stated that one or any desired number of refrigerating chambers may be employed.

Each of the chambers has approximately 90 centrally arranged therein a shelf 10, the said shelves being supported by corner posts 11. The posts are preferably in the nature of angle members, and are provided at points opposite the flanges of the shelves 10 with 95 openings that register with notches 12 in the flanges 10' of the shelves 10. Passing through the openings in the posts 11 are the shanks of headed threaded members 13 which are engaged by wing nuts 13'. The heads of 100 the members 13 are passed through the notches 12 and by adjusting the nuts the angle posts 11 will contact with the corner of the shelves, and the said shelves be effectively retained on the posts. This arrangement also permits of the removal of the posts from the shelves, so that the device may be collapsed or folded to provide a small package for shipment or storage, when not in use.

Each of the refrigerating compartments, 110 on the opposite sides of the shelf 10, is provided with pans. The pan for the upper

chamber is indicated by the numeral 14 and preferably has upon its lower face and at its corners, sockets 15 to receive the corner posts 11. The pan 14 is provided with spaced 5 openings which are surrounded by sleeves 16, and each of the sleeves has arranged therein a pivoted valve 17, the said sleeves and openings providing air inlets to the upper chamber 10 and the inlet of air is regulated by 10 the valves 17. The upper pan 14 is designed to receive thereon a water tank 18, the same having a funnel inlet 19, and an outlet cock 20. The valve of the cock 20 may be adjusted to regulate the outflow from the tank 15 18 into the pan 14. The funnel 19 may be removed from the tank 18, and the said tank inverted as illustrated in Fig. 5 of the drawings. The tank is retained at an angle by the arrangement of wedged shaped slidable 20 skids 50, arranged therebeneath. The adjustment of these skids regulates the level of the water in the draw pan 14, and the air pressure on the water is regulated by the adjustment of the cock 20.

25 As disclosed by the drawings, the corner posts of each of the chambers A and B are arranged at an inclination, the pan 21 which provides the lower wall for the upper chamber A as well as the upper wall for the lower chamber B, being of a larger size than the pan 14 that provides the top for the chamber A. The pan 21, adjacent the corners thereof is provided with openings through which pass sleeves 22, the said sleeves being secured 30 to the pan. Corner posts 11 are passed through the sleeves 22, and contacting with the opposite inner edges thereof, by virtue of the inclination of the said posts, hold the pan 21 on the said posts. The sleeves serve as 35 foul air outlets from the lower chamber B. The pan 21 is centrally provided with an opening normally closed by a plug 21', and through this opening the water from the pan may find an outlet, if desired.

40 The lower pan 24 is larger than the remaining pans and in reality provides the base for the construction. The pan 24, at its corners, is formed with depending legs 25, so that the said pan is elevated a suitable 45 distance above the ground or other supporting surface, and the pan 24 is provided with an overflow pipe 26 and an additional outlet opening normally closed by a plug 24'.

50 For each of the compartments A and B, I provide a closure in the nature of a fabric sheet, 27 respectively, both of the ends of the said sheets, being received in the respective upper and lower pans of the chambers A and B. The edges of these fabric 55 coverings overlap and are connected to the edges of the pans 14 and 21 by spring clips 51, the arrangement being such that access 60 may be obtained to the compartments in the chambers A and B. The upper end of 65 the cloth for the upper chamber being im-

mersed in the water in the pan 14 will become saturated and the water from the said saturated cloth will drip therefrom into the pan 21, immersing the upper end of the cloth for the lower chamber B, and the 70 said lower cloth will become saturated by capillary attraction, the water therefrom dripping into the base pan 24, finding an outlet through the overflow pipe 26. The 75 saturated cloths present evaporating surfaces to retain the compartments of the chambers in a cooled condition to preserve the articles arranged in the said chambers. The lower pans, being, at all times, partly 80 filled with water, are especially adaptable for the reception of crocks containing milk or butter to be cooled, while the shelves are designed to receive articles which might be effected by a direct contact with the water.

The water may be allowed to drip from 85 the tank 18 from the cock 20, as illustrated in Figs. 1, 2 and 3 of the drawings, but preferably the tank is arranged as illustrated in Fig. 5 of the drawings. It will be apparent that the water in the pan 14, 90 saturating the edge of the cloth or facing secured in the said pan will flow by capillary attraction over the upper cloth, saturating the edge of the lower cloth, and in a like manner flowing by capillary attraction 95 over the lower part. The tank when in the position illustrated in Fig. 5 requires no attention, except for the replenishing of the water therein. By adjusting the wedge shaped skid members 50 any desired 100 level of water may be obtained in the pan 14. The cloth facings permit of easy access being obtained to the compartments in the several chambers, and the said facings, when closed, will effectively protect the food products in the refrigerator against dust, vermin, or any other contaminating agencies, and furthermore, the reticulated vent sleeves will provide outlets for the odor from 105 the contents of the refrigerator and insure 110 the sanitation thereof.

Having thus described the invention, what I claim is—

1. An iceless refrigerator comprising a plurality of superimposed compartments 115 each including a shelf, and pans arranged at the top and bottom of each compartment, the pan providing the bottom wall of one of the compartments forming the adjacent wall of the other compartment, sleeves at 120 the corners of the intermediate pan, angularly disposed corner posts passing through the sleeves and frictionally contacting therewith, to support the intermediate pan, removable means for securing shelves to the 125 posts, a fabric casing for each of the compartments, clips for removably securing the casing to the upper pans of each of the compartments, a water containing tank on the top pan having a cock and an opening, and 130

removable and adjustable wedge members in the said pan underlying the tank to space the opening therein from the bottom of the pan whereby to control the outlet of water from the tank into the pan.

2. An iceless refrigerator comprising a plurality of superimposed compartments, each including a shelf, and pans arranged at the top and bottom of each compartment, the pan providing the bottom wall of one of the compartments forming the adjacent wall of the other compartment, sleeves at the corners of the intermediate pan, corner posts passing through 10 the sleeves and frictionally contacting there-

with to support the intermediate pan, shelves for the compartments, removable means for securing said shelves to the corner posts, a fabric casing for each of the compartments, means for securing said casings to the upper pans of the respective compartments, and means for delivering a fluid to the upper pan of the upper compartment to immerse the top edge of the casing thereof and permit of the fluid being delivered to the intermediate pan and to the casing for the lower compartment.

In testimony whereof I affix my signature.

THOMAS M. CHAPMAN.
